UNITED STATES PATENT OFFICE.

JOHN C. AUGUST RIECKÉ, OF BALTIMORE, MARYLAND, ASSIGNOR, BY DIRECT AND MESNE ASSIGNMENTS, TO THE COMMERCIAL MANUFACTURING COMPANY, INCORPORATED, OF BALTIMORE, MARYLAND.

COIN-CONTROLLED APPARATUS.

SPECIFICATION forming part of Letters Patent No. 732,115, dated June 30, 1903.

Application filed January 18, 1902. Renewed October 9, 1902. Serial No. 126,521. (No model.)

To all whom it may concern:

Be it known that I, JOHN C. AUGUST RIECKÉ, a citizen of the United States of America, residing at Baltimore, in the State of Maryland, 5 have invented certain new and useful Improvements in Coin-Controlled Apparatus, of which the following is a specification.

This invention relates to coin-controlled apparatus, and particularly to that class designed for use in vending or dispensing cigars or cigarettes.

The invention consists in the details of construction and in the arrangement and combination of parts to be hereinafter more fully 15 set forth and claimed.

In describing the invention in detail reference will be had to the accompanying drawings, forming part of this specification, wherein like characters denote corresponding parts 20 in the several views, and in which—

Figure 1 is a sectional view of a casing with the interior mechanism in elevation. Fig. 2 is a view in elevation of inside of the frame shown in Fig. 1. Fig. 3 is a vertical sectional 25 view taken on the line $\alpha\alpha$ of Fig. 1 looking in the direction of the arrow with some of the parts omitted for the purpose of distinctness. Fig. 4 is a central vertical section of the machine. Fig. 5 is an enlarged detail 30 view of the locking and releasing mechanism detached. Fig. 6 is a plan view of the plunger and slide.

In the drawings, A indicates the casing, which may be of any preferred construction, 35 to confine the vending mechanism proper, said casing having a glass portion a , through which the contents of the casing may be observed.

Duplicate frames B of irregular configuration 40 are connected by brace-rods b , and suitably-inclined supports c are secured to the inner surfaces of the frames for supporting a box or receptacle containing the cigars or cigarettes, it being understood that the incline of the supports may be varied for the 45 purpose of causing the contents of the receptacles to feed toward the delivering end. A sheathing of metal d is attached to the inner surfaces of the frame in order to confine the 50 box and the contents passing therefrom. The

sheathing also prevents the tobacco from gaining access to the operating mechanism.

A coin-chute E terminates at the top in a hopper e , which alines with the coin-opening F in the casing. A magnet f is supported 55 with its ends projecting into the chute for the purpose of arresting fraudulently-inserted keys for unlocking the mechanism. A guide f' projects into the chute and directs the coin close to the magnet. A slide G is 60 guided in the chute and has an upper cam-surface g , against which the coin acts to depress the same against the action of the springs H, which are connected to the slide and to the frame B, as shown in Fig. 1. The upper 65 end of the slide, as shown at h , forms a jaw for confining the guard I, which is pivoted at i to the inner wall of the chute, and another jaw J is connected to the slide by the plate j and serves to confine the guard until the 70 said jaw is carried down by the slide. A slide K is movable between the guides k , and a plunger L is connected to the slide K at its forward end, but is separated and stands away from said slide at the opposite end. 75 The plunger is provided with a cam-surface M, which acts against the coin m , causing said coin to depress the slide G, which carries the jaw J and permits the guard I to swing to the position shown in Fig. 5. In 80 case the coin m is not seated on the end of the slide G and the slide K is moved the end of the plunger will contact with the guard I, thus arresting the movement of the slide K in that direction, since said guard will be 85 held in its vertical position by the jaws h J . A lug G' is carried by the slide G, and when said slide is elevated the rear end of the rack-bar is engaged by the lug, so that said rack-bar cannot be moved; but as the slide is depressed the lug travels out of engagement 90 with the rack-bar and it is free to operate. A lever N is pivoted on the slide K on the side opposite the plunger, and an arm n is mounted on the shaft O, said arm being pivoted to 95 the lever N, whereby motion is imparted to the slide K when the shaft O is partially turned by means of the handle o . The edge of the arm is recessed near its lower end to receive a lug P of the rack-bar p , said rack-bar 100

being slideable in suitable guides, said rack-bar engaging a pinion Q on the shaft q, said shaft q having mounted thereon a deliverer R, which has a recess r, extending 5 longitudinally, for the reception of the article to be delivered. It will be seen that when the rack-bar is projected the deliverer R will be given a partial rotation to convey the contents of the recess r under the apron 10 S and deposit it on the incline s, from whence it rolls to the trough T in reach of the pur-chaser. The rack-bar carries an arm t with spring U connected, which extends back and is attached to the arm n, thus causing the 15 said rack-bar to retract when the operating-handle o is released. The rack-bar p has a handle extension p', which may be used to partially rotate the deliverer to agitate the contents of the receptacle, in which case the 20 apron may be dispensed with. A link V is pivoted to the arm t and to the arm v, said arm v being secured to the rock-shaft W, to which the apron S is secured. With each movement of the rack-bar the apron is moved, 25 swinging outwardly as the rack-bar is projected and inwardly as it is retracted. From an inspection of Fig. 4 it will be observed that the movement of the apron will agitate the cigars and prevent bridging or binding. 30 Fig. 4 also shows a flexible weight w, secured at one end to a brace-rod b and having at its opposite end a clasp X, which embraces the upper edge of the box containing the article to be vended. One of these flexible weights 35 is provided for each side of the box for the purpose of producing a positive feeding ac-tion and for retaining the contents in alinement. They also prevent jumping of the ci-gars and to a great degree prevent damage. 40 The plunger L has a projection from its lower edge which terminates in a point Y, with a cam-surface y, which causes the coin to be thrown into the chute Z, from whence it finds its way to the money-box z. The cam-surface M travels over the coin until the point 45 Y passes the highest surface thereof, when said coin will be thrown into the chute Z, as stated.

In operation when a coin is inserted in the 50 chute it is arrested on the upper end of the slide. As the operating-handle is turned, drawing the slide K, as heretofore stated, the plunger carried by the slide is brought into contact with the coin, and owing to the cam-55 surfaces of the slide and plunger the coin acts as a connection between the plunger and slide, and as the plunger continues to move the slide is depressed until the guard is released, and the plunger continues in the di-60 rection of its initial movement until the rack-bar is released from the lug on the slide, when by a further movement of the handle the rack-bar is reciprocated and the delivering mechanism set in motion. After the delivery 65 occurs the parts are returned to their normal positions by the springs H.

The construction and operation will, it is

thought, be understood from the foregoing de-scription, it being noted that various changes may be resorted to in the proportion and de-tail of construction for successfully carrying the invention into practice, especially with relation to the length and tension of the 70 springs.

Having fully described the invention, what 75 I claim as new, and desire to secure by Letters Patent, is—

1. In a vending-machine, a coin-chute, a slide therein having a cam end, a guard pivoted in the path of travel of the slide, means 80 whereby the guard is held in a vertical position when the slide is elevated, a plunger having a coin-engaging surface and with its path of travel controlled by the guard, means for moving the plunger toward the guard, 85 means whereby a coin between the cam end of the slide and cam-engaging surface of the plunger, operates to depress the slide and re-lease the guard, a rack-bar, means on the slide for holding the rack-bar against move-90 ment when the slide is elevated, and hand-operated mechanism for projecting the rack-bar when the slide is depressed, as and for the purpose described.

2. In a vending-machine, a chute, a slide 95 therein having a coin-engaging surface, a de-livering mechanism, a plunger having a pro-jection on its lower edge with camming-sur-faces extending in opposite directions, said plunger acting in conjunction with a coin to 100 depress the slide, a rack-bar held against movement when the slide is elevated and re-leased on its descent, a connection between the rack-bar and the delivering mechanism, 105 a rock-arm n, means for rocking said arm, connections between the rock-arm n, and the plunger, and a connection whereby the rock-arm projects the rack-bar, as and for the pur-pose described.

3. In a vending-machine, a coin-chute, a 110 slide therein having a cam edge, jaws carried by the slide, a guard held by the jaws, a plun-ger having a pointed extension with camming edges, for acting on a coin to depress the slide and eject the coin, a second slide carrying the 115 plunger, an operating-shaft, an arm thereon, a lever connecting the arm and plunger-car-rying slide, a rack-bar projected by the arm, a deliverer and a suitable connection where-by the movement of the rack-bar is commu-nicated to the deliverer, substantially as de-scribed.

4. In a vending-machine, a chute, a slide having a coin-engaging surface held normally 125 elevated in the chute, a plunger having coin-engaging camming edges, a guard, means on the slide for holding the guard in the path of the plunger, the said plunger acting on a coin to depress the slide and release the guard, 130 delivering mechanism released by the de-pression of the slide and means for actuating the delivering mechanism.

5. In a vending-machine, a coin-chute, a slide having a cam upper edge, a plunger

- having a cam edge terminating in a point and an oppositely-disposed cam edge, a guard held rigid in the path of the plunger when the slide is elevated and released on the descent of the slide, a rack-bar held against movement by the slide when in its elevated position, a delivering mechanism, means for moving the plunger and for actuating the delivering mechanism when a coin is inserted.
6. In a vending-machine, a coin-chute, a slide having a coin-engaging surface, a guard, means on the slide for holding the guard in the path of a plunger, a coin-engaging plunger coacting with a coin and the slide to re-

lease the guard, mechanism for moving the 15 plunger, a rack-bar locked by the slide when elevated and released on its descent, means for projecting the rack-bar, and delivering mechanism actuated by the projection of the rack-bar.

In testimony whereof I affix my signature, in the presence of two witnesses, this 18th day of January, 1902.

JOHN C. AUGUST RIECKÉ.
